UNITED STATES PATENT OFFICE.

ALBERT J. BATES, OF JOLIET, ILLINOIS.

KILN FOR DRYING BARRELS.

SPECIFICATION forming part of Letters Patent No. 554,973, dated February 18, 1896.

Application filed October 9, 1895. Serial No. 565,104. (No model.)

To all whom it may concern:

Be it known that I, ALBERT J. BATES, a citizen of the United States of America, residing at Joliet, in the county of Will and State of Illinois, have invented certain new and useful Improvements in Kilns for Drying Barrels, of which the following is a specification, reference being had therein to the accompanying drawings, and the letters and figures of reference thereon, forming a part of this specification, in which—

Figure 1 is a central vertical section. Fig. 2 is a horizontal section taken on line 1 of Fig. 1, looking down as indicated by the arrows. Fig. 3 is a perspective view of one of the compartments for holding a barrel. Fig. 4 is a side elevation of the swivel-joint of the steam-pipe, having a portion broken away to show the interior parts. Fig. 5 is a vertical section of the outer wall of the drying-chamber and a side elevation of a portion of one of the radiators of a barrel-compartment. Fig. 6 is a plan view of a plate for closing the perforations in the bottom of a barrel-compartment when opposite the door or opening for admitting barrels. Fig. 7 is a vertical section through the center of the two bearing-plates, showing roller-bearings between them for supporting the turn-table having the barrel-compartments.

This invention relates to certain improvements in a steam barrel-drying kiln, which improvements are fully set forth and described in the following specification and claims.

Referring to the drawings, A represents the side walls of a circular case or kiln intended to be made of brick or other masonry and having a roof, as shown in Fig. 1, provided at its apex with a chimney D, provided with a damper E for regulating a downdraft, as indicated by arrows.

B is a circular rotatable floor or table located within said walls A and supported at its center on pedestal H, as shown in said figure, through the medium of the roller-bearings J, located between the circular tracks K and K', as shown in Figs. 1 and 7, the track K resting on the top of the pedestal H and the track K' being attached to the under side of the floor B. Said rollers J are held in place by means of a band J' passing around them and inclosing them, and to which band

they are journaled by means of axle-studs, as shown in Fig. 7.

B² is an annular flange secured to the upper side of said floor B at some little distance from its periphery, as shown in Figs. 1, 2 and 3, which flange forms the inner walls of the barrel-compartments, which compartments are formed by means of the radial partitions B'.

Fig. 3 is intended to illustrate in perspective one of the barrel-compartments, and a description of one compartment will be sufficient for all, as all are duplicates of each other.

S is a steam-radiator located within the compartment and is arranged in a semicircular form to conform more to the shape of a barrel than if it were in the form of the compartment.

S' is a spiral steam-pipe connected with the upper part of the radiator and arranged to be immediately above the upper end of a barrel when it is in the compartment. The floor of each compartment is perforated, as shown at y' in Figs. 2 and 3, for the purpose of permitting a downward circulation of air through the compartment to the space under table or floor B through between the rollers J to pipe G leading to a chimney F, which chimney causes the draft through the barrel-compartments.

The steam-radiators S are each connected by means of the pipes P with an annular steam-pipe M, located within and near the flange B² above floor B, or on it, as may be desired. Said annular steam-pipe M is connected with a steam-supply pipe C C' through the medium of the pipe N and a swivel-joint L L', (shown more particularly in Fig. 4,) which swivel-joint is ordinary and permits the floor B to turn without breaking steam connection.

The inner side of the kiln is recessed, as shown in Figs. 2 and 5, for the purpose of holding in its recesses a series of steam-radiators T, which radiators are connected by means of pipes 1 1' 2 2' 3 with the steam-supply pipes C C'. Fig. 5 shows a portion of one of these radiators set in its recess and shows the pipes 2 3 for connecting it with the supply-pipe. The source of steam supply may be from an adjacent steam-boiler. (Not necessary to be shown.)

The wall or kiln A is provided at one side with an opening V, (shown in Figs. 1 and 2,) through which the barrels are introduced to their several compartments, and through 5 which they are removed when sufficiently dried.

R is a horizontal plate arranged, as shown in Fig. 1, to cover a compartment while opposite the opening V while a barrel is being 10 introduced or removed from its compartment for the purpose of preventing escape of warm air out through said opening, and said plate is of sufficient length to cover and extend a little beyond the compartment while opposite said opening, so that before one compartment has moved entirely from under it another compartment has begun to pass under it; and in order to prevent a rush of cold air through the opening V down through the 15 perforations y' a plate y is placed under the floor A immediately opposite the opening V, as shown in Figs. 1 and 6. Said plate rests on the inner ends of a pair of levers X, fulcrumed on arms W, projecting from the kiln 20 A. These levers are weighted at their outer ends, so that they press said plate up continuously against the bottom of the turn-table to close the perforations y' while opposite opening V and while a barrel is being introduced or removed, and thus prevent cold air 25 from rushing down under said floor and cooling it off.

In order to support the periphery of the rotatable floor B, a series of ports 5 are concentrically arranged at the center of the said floor and support a ring 4, which said ring is connected by means of guy-rods Z with the said floor near its periphery, as shown in Figs. 1 and 2. It is intended to turn said floor A 30 by hand; but it may be turned by any other means desired. The draft may be as well upward as downward, as the direction of the draft is not material.

In operation it is intended to introduce new 35 barrels into the barrel-compartments through the opening V consecutively as the table or floor A revolves, where the heat from the

steam-radiators will thoroughly dry the barrel after being left in their compartments a sufficient length of time, when after drying sufficiently they are removed through the opening 50 V and other barrels may in like manner be introduced and dried. The device is intended more particularly for new barrels.

Having thus described my invention, what 55 I claim as new, and desire to secure by Letters Patent, is as follows:

1. In a kiln for drying barrels the combination of the outer case A having a cover provided with an inlet controlled by a valve and 60 having an opening V, a rotatable floor B, arranged within said case and having the perforations y', flange B² and radial partitions B' arranged to form peripheral barrel-compartments on said floor, steam-radiators S S' arranged within said compartments and the pipes and swivel-joint for connecting them with a steam-supply, the radiators T arranged in recesses in the inner side of the wall A, and the pipes for connecting them with a steam-supply, the hollow pedestal H, circular tracks K K', and rollers J for supporting said rotatable floor on said pedestal-pipe G and chimney F, horizontal plate R and plate y and levers X all arranged to operate substantially 75 as and for the purpose set forth.

2. In a kiln for drying barrels a rotatable floor or table having peripheral barrel-compartments having perforated floors, and open at the top and outer side, a steam-radiator arranged within said compartments and the means for connecting them with a steam-supply, a case or outer concentric wall for enclosing said rotatable floor or table, and having steam-radiators arranged in its inner side 80 and the means for connecting them with a steam-supply, and the means for causing an air-draft to pass through the said barrel-compartments all arranged to operate substantially as and for the purpose set forth.

ALBERT J. BATES.
